UNITED STATES PATENT OFFICE.

KNUD GULBRANDSEN, OF CHICAGO, ILLINOIS, ASSIGNOR OF ONE-THIRD
TO CRISTIAN M. HANSEN AND ONE-THIRD TO EDWARD TORGERSON,
OF CHICAGO, ILLINOIS.

POWER-TRANSMISSION MEANS.

No. 840,985.

Specification of Letters Patent.

Patented Jan. 8, 1907.

Application filed April 16, 1906. Serial No. 311,945.

To all whom it may concern:

Be it known that I, KNUD GULBRANDSEN, a citizen of the United States, residing at Chicago, in the county of Cook and State of Illinois, have invented certain new and useful Improvements in Power-Transmission Means; and I do hereby declare the following to be a full, clear, and exact description of the invention, such as will enable others skilled in the art to which it appertains to make and use the same.

My invention relates to a novel construction in a friction-drive particularly adapted for automobiles to produce variable-speed gearing between the motor and the drive-shaft of the vehicle in either direction without varying the speed of the motor or reversing the same, the object of my invention being to provide a drive of this kind in which the pressure on the bearings of the crank-shaft of the motor is balanced, thus avoiding the excessive friction and rapid cutting out of the parts subjected to wear, with the use of friction-gearing now generally employed; and it consists in the features of construction and combinations of parts hereinafter fully described and claimed.

In the accompanying drawings, illustrating my invention, Figure 1 is a plan view of a friction-drive constructed in accordance with my invention. Fig. 2 is a side elevation of the same. Fig. 3 is a fragmentary detail perspective view. Fig. 4 is a fragmentary detail section, on an enlarged scale, on the line 4 4 of Fig. 3.

In said drawings, A indicates the crank-shaft, driven by the motor. At its opposite free ends said shaft A carries disks B, from which counter-shafts C, disposed parallel with each other, are driven. The latter are journaled in bearings D, movably disposed on the cross-bars E of the frame, as hereinafter described, and are suitably held against longitudinal movement therein. On each of said shafts a friction-disk F is mounted, the latter being longitudinally movable thereon, but held against revoluble movement relatively thereto in any suitable manner, preferably by means of a longitudinal groove G in said shaft C, into which a projection disposed on the hub of said disk extends. The hub of each of said disks F is provided with an annular groove H, which is adapted to be en-

gaged by suitable devices for imparting longitudinal movement to said disk, such means being common, and therefore omitted from illustration. The said bearings D are laterally movable and each of same carries a plunger J, which latter enters a sleeve K, disposed on a bracket L, mounted on each of the end portions of said cross-bars E, said plunger having a reduced free end and being provided with a collar M, between which and an annular shoulder N, disposed in said sleeve K, a spring O is disposed, which latter normally maintains said plunger J and said bearings D at the outer limits of their movement. The extreme free end of said plunger J is inclined in order to form a cam-face P.

Longitudinally movable in bearings K', disposed upon the outer free ends of the sleeves K, are rods Q, provided between their ends with recesses R, having one face disposed transversely to the axis thereof and the other face inclined and said inclined face being adapted to engage the cam-face P of said plunger J to force the same inwardly against the axis of said spring when said rod is moved in one direction. The said rod Q is preferably held against rotation relatively to said bearing L. The said rods Q are disposed parallel with said counter-shaft C, and each rod passes through two of said bearings L and is adapted to simultaneously engage both plungers J, carried by the adjacent bearings D of said counter-shaft. The said rods Q are moved simultaneously, thereby simultaneously shifting the positions of said bearings D relatively to said cross-bars E and forcing said disks F into peripheral contact with the outer faces of said disks B with greater or less pressure, as desired, the springs O serving only to normally maintain said disks F out of peripheral contact with said disks B. Any suitable means for simultaneously imparting longitudinal movement to said rods Q and to said disks F may be provided; but I have omitted illustration of such means as applied to said disks F, as I deem it unnecessary to go into needless detail, as this will be readily understood by any person skilled in the art. By imparting simultaneous movement to said rods Q by means of the rock-shaft S, journaled in the side bars T of the frame and likewise to the disks F when it is required to vary the speed-

gearing or reverse the same, the pressure and strains on said crank-shaft A are equalized, and the bearings thereof are obviously entirely relieved of any strain due to the pressure exerted by said disks F on said disks B. I am thus enabled to apply great pressure upon said disks B, and thus produce the friction necessary to transmit the power of the motor to the drive-gear of the vehicle or other machine without danger of hot bearings or other source of trouble, thus rendering my drive particularly adapted to the uses of automobiles.

I claim as my invention—

- 15 1. A friction-drive for transmitting power, comprising a main shaft geared to a source of power, disks rigidly mounted on the ends thereof, a counter-shaft disposed adjacent to and outwardly of each of said disks, bearings in which said counter-shafts are journaled at both ends, supports on which said bearings are movably disposed, means disposed in operative relation to all of said bearings to simultaneously impart movement thereto toward and away from the ends of said main shaft, and disks disposed on said counter-shaft and adapted to be maintained in per-

ipheral contact with the outer faces of said first-named disks.

2. A friction-drive for transmitting power, comprising a main shaft geared to a source of power, disks rigidly mounted on the ends thereof, a counter-shaft disposed adjacent to and outwardly of each of said disks, bearings in which said counter-shafts are journaled, 35 disks on said counter-shaft, supports on which said journals are movably disposed, springs disposed in operative relation to said bearings to maintain the same normally at the outer limits of their movements, and 40 means disposed in operative relation to said bearings for simultaneously moving the same against the action of said springs thereby imparting lateral movement to said shafts to force the disks thereon into peripheral contact with the outer faces of said disks on said main shaft.

In testimony whereof I have signed my name in presence of two subscribing witnesses.

KNUD GULBRANDSEN.
